Primary Examiner — Jack Reickel*Assistant Examiner* — Bobby W Jones, II(74) *Attorney, Agent, or Firm* — Martin & Ferraro, LLP(57) **CLAIM**

The ornamental design for a standing personal sanitizing device, as shown and described.

DESCRIPTION

FIG. 1 is a front, top and right perspective view of a standing personal sanitizing device, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken line portions show unclaimed subject matter only and form no part of the claimed design.
